[57] CLAIM

The ornamental design for a cup holder, as shown and described.

DESCRIPTION

FIG. 1 is a right-side view of a cup holder in accordance with my invention;

FIG. 2 is a front view of the cup holder shown in FIG. 1;

FIG. 3 is a rear view of the cup holder shown in FIG. 1;

FIG. 4 is a top plan view thereof;

FIG. 5 is a bottom view of the cup holder shown in FIG. 1;

FIG. 6 is a left-side view of the cup holder shown in FIG. 1; and,

FIG. 7 is a right side elevational view of the article shown in use with the broken line showing of a cup being for illustrative purposes only and forming no part of the claimed design.

The contrasting shading shown on the band in FIGS. 1, 3, 6 and 7 is understood to represent an elastic surface.

FIG. 3

FIG. 4

FIG. 1

FIG. 5

FIG. 2

FIG. 7

FIG. 6
